UNITED STATES PATENT OFFICE.

LOUIS OTTROSINKA, OF LACKAWANNA, NEW YORK, ASSIGNOR OF ONE-HALF TO ANNA M. McDUGAL, OF BUFFALO, NEW YORK

RAIL-FASTENER.

1,184,769.

Specification of Letters Patent.

Patented May 30, 1916.

Application filed February 4, 1916. Serial No. 76,091.

To all whom it may concern:

Be it known that I, LOUIS OTTROSINKA, a citizen of the United States, residing at Lackawanna, in the county of Erie and State of New York, have invented new and useful Improvements in Rail-Fasteners, of which the following is a specification.

One of the objects of my invention is the provision of a strong and reliable joint or fastener which will prevent spreading of the rails and firmly hold their adjoining ends in place.

A further object is the provision of a fastener which will dispense with bolts or other separate fastening means, thereby eliminating the usual holes in the end-portions of the rails which tend to weaken them.

In the accompanying drawings: Figure 1 is a perspective view of the fastener applied to the rails. Fig. 2 is a transverse vertical section thereof taken through one of its end portions. Fig. 3 is a similar section taken through its central portion. Fig. 4 is a perspective view of the inner fastening member. Fig. 5 is a fragmentary perspective view of the outer fastening member. Fig. 6 is a similar view of one of the rails, showing the means for interlocking it with its support.

Similar characters of reference indicate corresponding parts throughout the several views.

10 indicates the adjoining ends of the rails. Applied to the inner and outer sides of the rails are fastening or clamping members each preferably comprising a pair of transverse end pieces 11 arranged on opposite sides of the meeting ends of the rails 15 and rigidly connected together by a longitudinal tie or space-bar 12 formed integral therewith. These end pieces and tie bars are constructed to fit snugly against the sides or webs of the rails between the customary tread and base-flanges, as shown in Figs. 1, 2 and 3, so as to interlock with the rails and prevent vertical movement of said members relative to the rails. The rails and said end pieces rest upon transverse rail-supports or plates 13 which are preferably seated in recesses formed in the upper face of the tie 14 and secured in place thereon by spikes 15 or other suitable fastenings. Extending upwardly from each of these 55 rail-supports and preferably above the base-

flanges of the rails, are a pair of lugs 16 arranged on opposite sides of the rail and projecting into sockets or recesses 17 formed in the undersides of the corresponding end pieces 11. The fastening members are thus 60 interlocked with said lugs and held against displacement thereon in a horizontal plane, firmly holding the rails and preventing spreading thereof. To facilitate the entrance of the lugs into said sockets, these 65 parts are tapered, as shown.

As illustrated in Figs. 2 and 6, the base flanges of the rails are provided in opposite edges with locking notches or recesses 18 arranged to receive the adjacent base- 70 portions of the lugs to prevent longitudinal displacement of the rails on their supports. If desired, these notches may be omitted, and the lugs 16 spaced farther apart to bear 75 against the unnotched edges of the base flanges of the rails. As the lugs snugly fit the sockets or recesses 17, they prevent the fastening members from tilting away from the rails, thus dispensing with the use of bolts or other additional fastenings for this 80 purpose. The lugs are also long enough and arranged in sufficiently close proximity to the sides of the rail to avoid such tilting.

As shown at 19, Fig. 2, the top of the inner fastening member terminates below 85 the ball or tread-flange of the rails to permit the wheel-flanges to clear said members. The outer fastening member preferably extends to the top of said tread-flange, as shown, to more firmly hold the ends of the rails in 90 place, and for this purpose, said member is provided in its inner face with a longitudinal groove 20 which receives the tread-flange.

In using this device for fastening the intermediate portions of the rails, the longitudinal tie-bars 12 of the end pieces 11 are omitted and one of the rail-supports 13 is placed upon each tie, the lugs 16 of said supports entering the sockets 17 of the end pieces, as before described.

It will be seen by reference to Fig. 2, that the lugs of the outer fastening member are preferably somewhat larger than those of the inner one, for the reason that the outward strain on the rails exerted by a passing train is greater than the inward strain.

In assembling the parts of the joint, the adjoining ends of the rails are elevated above the lugs of the rail-supports 13. The 110

- inner and outer fastening members are then placed against the sides of the rails and the latter together with the fastening members are lowered upon said supports to pass the 5 socketed end pieces 11 over said lugs, thereby interlocking the fastening members with the supports and reliably holding the rails against lateral and longitudinal displacement, as hereinbefore described.
- 10 To disconnect the rails, they are simply elevated to withdraw the fastening members from engagement with the lugs 16 of the rail-supports, whereupon said members may be removed from the rails.
- 15 As no bolts or similar fastenings are required by the use of this joint, its cost is correspondingly lessened, and it is safer and more reliable than joints employing such fastenings.
- 20 I claim as my invention:
1. The combination of a rail having a tread-flange and a base-flange, a support for the rail having a lug extending upwardly therefrom, and a fastening-member constructed to engage the rail between its tread and base flanges to prevent independent vertical movement of the rail and said member, said fastening member having in its underside a socket which receives said lug, where- 25 by the fastening member is held against lateral displacement relatively to said support, the rail and the fastening member being capable of upward movement independently of said rail-support to disengage said socket 30 from said lug.
  2. The combination of a rail having a tread-flange and a base-flange, a support for the rail having a lug extending upwardly therefrom, and a fastening-member constructed to engage the rail between its tread and base flanges to prevent independent vertical movement of the rail and said member, said fastening member having in its underside a socket in which said lug is closely 40 fitted, said lug extending upwardly far enough and being arranged in sufficiently close proximity to the side of the rail to prevent tilting of the fastening member relatively to the side of the rail without the use 45 of additional fastenings.
  3. The combination of adjoining rails having tread and base-flanges, transverse rail-supports arranged on opposite sides of the joint between the rails and each having an upwardly-extending lug, and a removable fastening member extending across the meeting ends of the rails and constructed 55 to engage the same between their tread and base flanges, said members having end pieces provided with recesses which receive the 60 lugs of said rail-supports.
  4. The combination of adjoining rails having tread and base-flanges, transverse rail-supports arranged on opposite sides of the joint between the rails and provided on 65 opposite sides of the rails with upwardly-extending lugs, and fastening members engaging opposite sides of the adjoining rails between the tread and base-flanges, each of said members comprising end-pieces provided with recesses which receive the lugs of the corresponding rail-support and a tie-bar connecting said end pieces and extending across the meeting ends of the rails.
  5. The combination of a rail having a 75 tread-flange and a base-flange, a support on which said rail rests having a lug extending upwardly therefrom, a fastening member provided with a recess into which said lug slidably extends, said recess having a continuous wall, said fastening member being removable through upward movement and engaging the rail intermediate the tread-flange and base-flange, said parts forming the sole fastening means employed, the engagement of the fastening member with said flanges preventing independent vertical movement of the rail and fastening member, and the recess-and-lug connection preventing lateral displacement and tilting of the 80 fastening member, whereby the use of fastening bolts or the like to prevent tilting of the fastening member is avoided.
  6. The combination of a rail having a 85 tread-flange and a base-flange, a support on which said rail rests having a lug extending upwardly therefrom and above said base flange, a fastening member provided with a recess into which said lug slidably extends, said recess having a continuous wall, said 90 fastening member being removable through upward movement and engaging the rail intermediate the tread-flange and base-flange, said parts forming the sole fastening means employed.
  7. The combination of a rail having a 95 tread and a base flange, a support on which said rail rests having a lug projecting upwardly therefrom, said base-flange having a notch which interlocks with said lug, and a 100 fastening member engaging said rail intermediate said tread and base flanges and provided in its underside with a socket which receives said lug.

LOUIS OTTROSINKA.
